UNITED STATES PATENT OFFICE.

JOHN M. CALLOW, OF SALT LAKE CITY, UTAH, ASSIGNOR, BY MESNE ASSIGNMENTS, TO
METALS RECOVERY COMPANY, A CORPORATION OF MAINE.

ORE-CONCENTRATING APPARATUS.

1,141,377.

Specification of Letters Patent. Patented June 1, 1915.

Application filed October 6, 1913. Serial No. 793,695.

To all whom it may concern:

Be it known that I, JOHN M. CALLOW, a subject of the King of Great Britain, residing at Salt Lake City, in the county of 5 Salt Lake and State of Utah, have invented certain new and useful Improvements in Ore-Concentrating Apparatus, of which the following is a specification.

My invention relates to a certain new and 10 useful process of and apparatus for the concentration of metallic ores by separating the valuable metallic particles from the barren or rocky constituents thereof, as I will hereinafter described and claim.

15 In the accompanying drawings forming part of this specification and in which similar reference characters indicate like parts in the several views; Figure 1 illustrates a side elevation of an apparatus for the concentration of ores embodying my invention. Fig. 2 is a similar view of a series 20 of tanks or agitating chambers on an enlarged scale showing certain of the chambers in section. Fig. 3 is a top plan view 25 of Fig. 2.

This invention is distinguished from the usual amalgamation processes in which the ore forms an amalgam and it relates more particularly to what is now known as the 30 flotation process, wherein a certain percentage of oil or of two dissimilar oils, or an oil and an acid, or an oil and an alkali, is mixed with finely ground ore pulp and the mixture then subjected to a violent agitation by means of mechanical propellers. The result is that large quantities of air are 35 beaten into and entrained by the pulp, which action produces a froth composed of bubbles of air and oil to which the mineral particles are attached. This froth has the 40 appearance of an aggregation or mass of fine and small soap bubbles which, when collected and the froth discharged or broken down, by natural settlement or by the addition 45 of cold water, or other means, displaces the mineral particles that have been caught.

The secret of successful flotation of ore 50 particles, aside from the proper percentage of oil or other reagents, is the beating of large volumes of air into the pulp, because in the absence of air no froth will be formed, and in order to obtain the desired aeration 55 of the pulp, mechanical stirrers, or pro-

pellers have been adopted and are now in more or less general use in this art. 55

A leading object of the present invention is to simplify the aforesaid flotation process by eliminating therefrom the mechanical propellers, or agitators, for impregnating the pulp with the large volume of air which 60 seems to be necessary, or, desirable, for aerating the pulp, and to this end the process portion of my invention has in view the addition to the pulp containing the proper percentage of oil, or other reagent, of compressed air which is introduced into the pulp from beneath through some porous body, and in innumerable fine streams or jets, for the purpose of both aerating and agitating said pulp. The compressed air 70 thus becomes the medium of (1) fully aerating or charging the pulp with the desired volume of air, and (2) it likewise induces and maintains that agitation of the pulp which heretofore was obtained by the 75 mechanical propellers and stirrers before alluded to. As just stated, I introduce the compressed air into the pulp from below, and I admit this air to the pulp through a porous body to thereby subdivide the air 80 into innumerable fine streams. The advantage of these steps will be understood and appreciated from the following: It might be imagined at first that equally good aeration could be accomplished by introducing 85 air through a number of jets, say arranged about three inches apart, but this will not work satisfactorily as the volume of air necessary to do the agitation, going through a restricted number of jets, would be so much 90 in volume from each jet as to cause a balloon of air, which, instead of making the froth, would destroy it, as the balloons of air would be too large to be maintained and would rise to the surface and burst, where- 95 as when the jets are innumerable in number and infinitely small in size, the balloons are correspondingly small, and are so small that when they rise to the surface they will not burst, but will continue to accumulate 100 and so form the froth which is the main object I have in view.

In the drawings I have shown for illustrative purposes one type of apparatus which may be successfully used in carrying 105 out my process, but it will be understood

that other and specifically different types of apparatus can also be used and hence I consider it within the scope of my invention to use any apparatus which will enable me to perform therein the several steps of my process and particularly that important step thereof which includes the passage of air under pressure through a porous body, L, of whatever nature, which will have the function of splitting up the air into innumerable fine streams, and distributing these fine streams over the entire surface of the vessel containing the pulp, whereby immediately upon the introduction of the air, a violent agitation or ebullition takes place and a froth begins to generate and to finally rise and form on the surface of the pulp, from which it is discharged, as I will hereinafter describe.

Referring now to the accompanying drawings, A, is a feed-tank of any suitable character supported upon a framework which will elevate the tank a sufficient height to insure a satisfactory gravity feed of the pulp to the balance of the apparatus, it being understood that this tank is adapted to receive ore-pulp together with its carrying water and which pulp may be fed to the tank through a pipe line, A', as indicated in Fig. 1. Disposed adjacent and above the feed tank is a vessel, C, adapted to contain one of the reagents, which I will call oil.

D is a vessel adapted to contain another reagent, which I will call an acid, said vessels, C, and D having suitable cocks or valves, by which the percentage of reagent, say oil and acid, admitted with the ore-pulp and water may be regulated, as desired. The oil, the acid and the pulp mix in the feed tank, A, and are conveyed therefrom by a pipe, E, to the first of a series of tanks or receptacles in which the pulp is agitated and aerated. I have shown four of these tanks or receptacles, F', F², F³ and F⁴, for illustrative purposes, but it will be understood that the number of tanks used may be increased or diminished from what I have shown, without in any manner departing from the spirit of my invention.

The tanks or receptacles are preferably constructed alike and each consists of an outer casing of suitable form, dimensions and construction, and an interior casing K, of smaller size and spaced from the walls of the outer vessel to form a circumscribing space, M, the purpose of which will hereinafter appear, said inner casing having, preferably, a flaring or funnel-shaped upper end.

In the upper part of the tank or receptacle, F', is suitably secured an inverted cone, S, the top or smaller end of which is disposed below the top of the tank, said cone having its lower part connecting with the inner wall of the tank so as to form a

gutter, S', in the upper portion of the tank between the cone and the inner wall of said tank. This gutter or launder, S', terminates in a spout, G, Fig. 3, at one side, and the spouts of the several tanks or receptacles, 70 F', F², and F³, which as before stated are similar in construction and arrangement, connect with a side launder or trough, H, which conveys the contents of the several gutters or launders, S', into an appropriate 75 feed box, I, from which box the contents are delivered by a pipe or down-take, J, into the final tank or receptacle, F⁴, which I will hereinafter designate as a "cleaner," while the first three of the tanks, F', F² and 80 F³ I designate as "roughers." As before stated, the tanks have substantially the same design and construction, and the frothy concentrates made on the first three of the tanks are conducted by the side launder or 85 trough, H, into the feed box, I, and then are conducted into the cleaner, F⁴, through the pipe, J.

In the lower portion of the inner casing, K, of each tank or receptacle and elevated a 90 suitable distance above the bottom thereof, is a porous medium, L, which is supported upon suitable brackets, or other rests, L'. By elevating this porous medium above the bottom of the tank or receptacle, I am permitted to form between the bottom of said medium and the bottom of the tank, a chamber, P, which is cut off from communication with the upper portion of the tank, and with the pulp contents thereof, except 95 through the pores of the medium, L, and which medium is centrally pierced to admit the upturned end of the pipe, F, which conducts the pulp from the feed-tank into the pulp chamber of the tank, F'. Thus the feed coming through the pipe, E, is prevented from entering the space below the porous medium, but is allowed to discharge itself through the upturned end of the pipe, and directly into the main chamber of the 101 vessel above said porous floor, or medium, L, referred to. In practice, the pulp is allowed to run into the tank or receptacle, until the latter is partly filled, the level of the water being variable according to the 11 conditions of the ore and the work to be accomplished.

As before stated, a space, M, is formed between the inner and outer casings of each tank, and this space forms a gutter or channel which connects with a discharge pipe, N, having a valve, O, which controls the height of the water in the vessel by restricting the discharge. In other words, by the regulation of the valve, O, in relation to 12 the amount of feed, any level of pulp in the vessel, F', can be maintained. The pipe, N, from tank or receptacle, F, leads into the second tank, F² and through the porous medium, L, therein and the discharge from 13

this second tank likewise leads into the third tank, and so on, until in the final tank or "rouger," F³, the discharge will be through the pipe, W, said discharge being discarded 5 and allowed to go to waste.

Compressed air is designed to be introduced into the chamber formed below the porous medium, L, in each of the tanks or receptacles, including the "cleaner," F⁴, and 10 to this end, I admit the compressed air through a pipe, Q, from which a valve-controlled branch, Q', leads through the bottom of the tank and into the space, P, between the same and the under part of the 15 porous medium, L. To prevent the air from impinging directly upon the porous medium immediately above the inlet end of the pipe, Q, I place over the discharge end of the pipe a shield or deflector, R. The pipe, Q, may 20 be otherwise disposed, but in any event its function is to admit into the chamber between the bottom of the porous medium and the bottom of the tank proper, a volume of compressed air.

25 The porous medium may be of any suitable construction and material; porous brick, or a layer of fine sand between two restraining layers of screen cloth, or layers of fibrous material laid one above the other, such for instance as cocoa matting, or certain kinds of porous wood, such as bamboo, may be used, or in fact any porous material through which air can be forced in more or less irregular jets of infinite number and 30 fineness. The character of the porous material employed is, therefore, unimportant, except that it shall have the property of permitting the air introduced into the chamber, P, to be discharged through the pores of 35 the material throughout the entire surface thereof, and into the body of pulp in the chamber above, with the result that immediately upon the introduction of the air, a violent agitation or ebullition takes place, 40 and froth is observed to rise and form on the surface of the pulp contents, which greatly increases in volume and density as the action proceeds. As the froth accumulates above the surface of the pulp within 45 the vessel, F', it overflows the rim of the inside top cone, S, and continues to do so as long as the tank or vessel is supplied with the necessary ingredients of pulp, oil, acid 50 and compressed air, and the overflowing 55 froth is received into the gutter or annular launder, S', and finally is delivered into the feed-box, I, through the side launder or trough, H. During this agitation of the pulp and the formation of the froth, the 60 tailings settle into the annular space, M, formed between the tank and the inner casting, K, thereof, and the discharge of these tailings takes place through the discharge pipe, N, and through which pipe, the particles which are too heavy to float in the first

tank and which have settled into the annular space, M, thereof, are delivered into the succeeding tank, F², this action occurring in all of the tanks, and the waste material being delivered from the final or "roughing" 70 tank, F³, through the discharge pipe, W, before mentioned. In other words, the discharge from the first tank, F⁴, makes feed for the succeeding tank, F², and the discharge from the latter in turn makes feed 75 for the next tank, F³. Each of these tanks in turn makes a frothy concentrate in the manner before described, and the froth of the several tanks is in turn led to the feed-box, I, from which latter it is discharged 80 into the "cleaner" tank, F⁴, where a similar action occurs, and the rough or crude concentrates made on the first series are cleaned, or further refined by a similar action in the tank, F⁴, the concentrates being discharged 85 therefrom through a side launder, U, and the tailings being delivered from the bottom of the tank, F⁴, by means of a siphon-pipe, or otherwise.

It is customary to conduct the discharge 90 from the "cleaner" tank, F⁴, back to the original feed so that it may be again and again acted upon, and to this end, I have shown in Fig. 1, the use of a pump, 10, for conducting the discharge from the cleaner 95 tank back to the feed tank, A, through the medium of a suitable pipe, 11. It will also be observed that in each of the tanks between the flaring top of the inner casing, K, and the top of the cone, S, I have shown 100 three or more diaphragms, X', X² and X³. These diaphragms extend clear across the pulp chamber and are arranged in parallel order and are perforated; the perforations may be of the same size, or they may vary 105 in fineness from the diaphragm, X', to the diaphragm, X³, the lowermost of the diaphragms having the coarsest perforations and the uppermost diaphragm the finest. These perforated diaphragms form baffles 110 and serve the purpose of preventing eddies or isolated or segregated currents within the machine. At the same time they serve the purpose of sustaining the froth and though not indispensable to the forming of 115 the froth, yet at the same time, they have the effect of increasing the efficiency of the apparatus.

From the foregoing it will be understood that no mechanical propellers are used for 120 producing the necessary agitation and beating into the froth of large volumes of air and which propellers usually require all the way from 7 to 15 H. P., to operate. Thus the power and the wear and tear incident 125 to the machinery usually employed to agitate the pulp has been entirely done away with in my apparatus and the only power necessary to both agitate and aerate the pulp, in my invention, is the small amount 130

of compressed air used in the agitation, which would not be more than 1/10 of that required by mechanical propellers. The simplicity of my apparatus is self-evident. 5 Its efficiency also is much higher in the recovery of the values, as instead of depending upon the hit or miss method of forcing air into pulp by means of mechanical agitators, the air is introduced in the more simple and 10 logical manner herein described, namely, in the form of innumerable fine streams or jets which are distributed over the entire surface of the vessel containing the pulp, it having been found by experiment that by 15 admitting a large volume of air in the form of innumerable fine streams I fully impregnate the pulp with the air and cause the formation of froth in the form of fine bubbles of air enveloped in the reagent and which bubbles are so small that when they rise to the 20 surface they will not burst, but will continue to accumulate so that they may overflow and be delivered through the launders before mentioned.

25 Having thus described my invention what I claim as new and desire to secure by Letters Patent is:—

1. In apparatus of the character described, the combination of a tank or receptacle adapted to receive ore pulp and a substance having the property of frothing in the presence of a gaseous medium and agitation, a casing within the lower portion of the tank and separated therefrom to form 30 a surrounding space or chamber, a body of porous material within said inner casing and supported above the bottom thereof so as to form a chamber between said porous body and the bottom of the tank, a feed-pipe 35 terminating in the lower portion of the tank above the porous body and adapted to deliver the pulp into the casing above said body, a pipe leading into the chamber below said porous body and adapted to admit a 40 gaseous medium under pressure thereto, said porous body subdividing the gaseous medium and distributing the same irregularly substantially throughout the entire surface of the pulp, and a discharge means 45 connecting with the space or chamber between the inner casing and the tank and adapted to deliver therefrom the heavier material which has settled into said space. 50

2. In apparatus of the character described, 55 the combination of a tank or receptacle adapted to receive ore pulp and a substance having the property of frothing in the presence of a gaseous medium and agitation, a casing within the lower portion of the tank and separated therefrom to form a surrounding 60 space or chamber, a body of porous material within said inner casing and supported above the bottom thereof so as to form a chamber between said porous body and the bottom of the tank, a feed-pipe 65

minating in the lower portion of the tank above the porous body and adapted to deliver the pulp into the casing above said body, a pipe leading into the chamber below said porous body and adapted to admit a 70 gaseous medium under pressure thereto, said porous body subdividing the gaseous medium and distributing the same irregularly substantially throughout the entire surface of the pulp, and a discharge means 75 connecting with the space or chamber between the inner casing and the tank and adapted to deliver therefrom the heavier material which has settled into said space, said inner casing having a flaring upper end. 80

3. In apparatus of the character described, the combination of a tank or receptacle, adapted to receive ore pulp and a substance having the property of frothing in the presence of a gaseous medium and agitation, a 85 casing within the lower portion of the tank and separated therefrom to form a surrounding space or chamber, a body of porous material within said inner casing and supported above the bottom thereof so as to 90 form a chamber between said porous body and the bottom of the tank, a feed pipe terminating in the lower portion of the tank above the porous body and adapted to deliver pulp into the casing above said body, a pipe leading into the chamber below said porous body and adapted to admit a gaseous medium under pressure thereto, said porous body subdividing the gaseous medium and distributing the same irregularly substantially throughout the entire surface of the pulp, a discharge means connecting with the space or chamber between the inner casing and the tank and adapted to deliver 95 therefrom the heavier material which has settled into said space, and a cone-shaped member in the upper part of the casing below the top thereof and through which the accumulating frothy contents of the tank pass and over which they are discharged. 100

4. In apparatus of the character described, the combination of a tank or receptacle adapted to receive ore pulp and a substance having the property of frothing in the presence of a gaseous medium and agitation, a casing within the lower portion of the tank and separated therefrom to form a surrounding space or chamber therebetween, a body of porous material within said inner casing and supported above the bottom thereof so as to form a chamber between said porous body and the bottom of the tank, a feed pipe terminating in the lower portion of the tank above the porous body and adapted to deliver pulp into the casing above said porous body, a pipe leading into the chamber below said porous body and adapted to admit a gaseous medium under pressure thereto, said porous body subdividing said gaseous medium and distrib- 115 120 125 130

utting the same irregularly substantially throughout the entire surface of the pulp, a discharge means connecting with the space or chamber between the inner casing and the tank and adapted to deliver therefrom the heavier material, which has settled into said space, a conical member in the upper portion of the casing forming a surrounding gutter between itself and the inner wall 10 of said tank and into which gutter the froth

produced in the tank is allowed to overflow, and means for conducting the froth from said gutter.

In testimony whereof I affix my signature in presence of two witnesses.

JOHN M. CALLOW.
